INTERLOCKING SYSTEM FOR RAILROADS

Filed March 20, 1930

UNITED STATES PATENT OFFICE

FRANK L. DODGSON, OF ROCHESTER, NEW YORK, ASSIGNEE TO GENERAL RAILWAY SIGNAL COMPANY, OF ROCHESTER, NEW YORK

INTERLOCKING SYSTEM FOR RAILROADS

Application filed March 20, 1930. Serial No. 437,472.

This invention relates to power interlocking systems, and more particularly pertains to the remote control of switch machines and signals used in such systems, and to the electric interlocking between such remotely controlled functions.

In interlocking plants, where a large number of switch machines and signals are governed from a central tower, it is desirable for reasons familiar to those skilled in the art, to have those signals governing traffic over a particular track switch dependent upon the position and locked condition of that switch. It is further desirable that all such governing signals shall give their most restrictive indications before the associated track switch is allowed to be operated to a new position.

Also, in interlocking plants, any one particular track section may be included in a large number of the possible route combinations, which makes it desirable to provide each of the signals, controlling traffic over a given section, with individual control. In other words, the clearing of the signals governing a certain route may be dependent and interlocked with the associated switch machines and still be dependent upon individual control to establish the final clearing and the direction of traffic to be set up over that route, as distinctive from that type of remote control in which the sequence of operation and the presence of a train establishes the direction of traffic over a given route.

With the above and other considerations in mind, it is proposed to provide in accordance with the present invention an interlocking system of the remote control type having the switch machine and signal circuits interlocked to prevent control of the switch machine until the associated signals give most restrictive indications. The interlocking system is to be further provided with individual control of the signals, which control is also interlocked with the associated switch machine. Also, the switch machine remote control circuit is to be organized to prevent the control lever in the tower from being operated out of correspondence with the circuit controlling relay associated therewith.

Another object of the invention, is to pro-

vide that the relay indicating the position and locked condition of a particular track switch, shall also indicate the correspondence of the remote control relay, the remote controller and the signals with the position and locked condition of that particular track switch.

Various other objects, purposes and characteristic features of the present invention will be in part obvious from the accompanying drawing, and in part pointed out as the description of the invention progresses.

The single figure of the accompanying drawing represents in a diagrammatic manner one specific interlocking system with its circuits and devices arranged and constructed to embody the present invention.

With reference to the single figure of the drawing, a track switch TS is conventionally shown as operated by a suitable switch machine included within the dotted rectangle SM. This switch machine SM is preferably of the type described in the patent to W. K. Howe Patent No. 1,466,903, dated September 4, 1923, but may be any other suitable switch machine having the usual armature A and field winding F and being capable of operating said track switch TS to either of two extreme locked positions. Also, included within the switch machine SM is a brake BR normally biased to a braking position and included within the operating circuit of the switch machine SM, so that it will be actuated to a released condition upon the application of power to said switch.

A movable contact 5, which makes contact between a pair of fixed contacts when in a normal position and a certain other pair of fixed contacts when in the reverse position, is caused to assume these positions in correspondence with the switch machine SM at the end of each of its operations.

The contacts, shown within a dotted rectangle designated PD, are known as point detector contacts, and include a movable contact block 6 of insulating material which is caused to assume extreme normal or reverse positions when the track switch TS is in corresponding positions and locked; and which is caused to assume an intermediate posi-

tion when the track switch TS is being operated from one extreme position to another, or any other such time that said track switch is unlocked. Contacts 7 and 8 are mounted on this movable contact block 6, which make contact between their respective pairs of fixed contacts when in the normal or reverse extreme positions only.

The point detector contacts PD include, a shunt contact 9 which is actuated to a non-contacting position when the contact block 6 is in a normal extreme position and assumes a biased contacting position at any such time that said movable contact block 6 is not in an extreme normal position; and also, a shunt contact 10 which is actuated to a non-contacting position when the movable contact block 6 is in a reverse extreme position and assumes a biased contacting position at any such time that said movable contact block 6 is not in an extreme reverse position.

Associated with the switch machine SM is a circuit controller CR of the mechanical stick or toggle type circuit controller which is operated by a control relay Z¹ which in turn is controlled from the interlocking tower TR. The conditions, under which the remote controller CR may be operated, are determined by the positions assumed by a switch repeater relay SR and normal and reverse indication repeating relays NI and RI respectively associated with the contacts PD.

A normal operating coil NC and a reverse operating coil RC serve to operate a plurality of contacts of the controller CR to corresponding normal or reverse positions respectively, in which positions said contacts are both electrically and mechanically held until the next succeeding operation.

The track switch TS allows traffic to be routed over the main track represented by rails 1, or allows traffic to be routed onto a passing siding PS represented by rails 2. A detector track section TE is associated with the main track and the fouling portion of the passing siding and has the usual track battery 13 and track relay T. At the west end of the detector track section TE, signals S^a and S^b, each being capable of giving two or more indications, govern the traffic passing in an east bound direction over the main track or the passing siding respectively, in accordance with the position of the track switch TS as indicated by the indication relays NI and RI, and also in accordance with the position of a remotely controlled relay Z² which is controlled from the tower TR.

Associated with the track relay T and the remotely controlled relays Z¹ is a section locking relay SLR which is energized through a circuit including the front contact of the track relay T and such other relays, for example, as approach locking relays, route locking relays, and the like, (not shown) commonly used in interlocking circuits. The relay Z¹

is of the polar magnetic stick type, that is, when its contacts are operated to an extreme position, they are held in that position by a permanent magnet. Similarly, the relay Z² is of the polar-neutral type in which the polar contacts operate the same as the polar contacts of relay Z¹, and in which a neutral contact assumes the same actuated position each time that the relay Z² is energized.

In the interlocking tower represented by the dotted rectangle TR, a miniature track diagram corresponding in every particular to the actual track layout of the interlocking plant includes a miniature passing siding ps and detector track section te. An indicator light I, located above the track section te, indicates the occupancy of the detector track section TE associated therewith.

A switch machine lever SML is provided for controlling the track switch TS from the tower. This lever SML operates a switch of the two-position quick acting tumbler type having a lock L which, when deenergized, prevents movement of the switch contacts to a new position. The position of the lever SML determines the application of positive or negative potential upon a control circuit including an indication relay IR from any suitable source such as battery BT¹ having its midpoint connected to a common wire C¹. A signal lever SL operates a switch of the three-position type for placing positive or negative potential from any suitable source such as battery BT² upon the control circuit of relay Z² located at the switch machine for governing the signals S^a and S^b.

It will be noted, that throughout the description of this embodiment of the present invention, that the opposite terminals of all sources of electrical potential will be designated as B+ and B-, which sources may be the same sources of supply or other suitable sources all in accordance with the practical application of the invention. It is to be understood that these sources of electrical potential are preferably local to the points indicated, also that they may be either direct current or alternating current according to the circumstances to be met in practice.

It is believed that the usefulness of the system and the interrelated functions of the various circuits and devices will be more readily understood by further description being given from the standpoint of the operation of the interlocking system taken as a whole.

Operation of the system

The interlocking system is shown in the normal condition with the track switch TS in a normal position and locked by the switch machine SM. This condition is indicated by the switch repeating relay SR in such a manner that the signal S^a may be cleared, that is, caused to give indication advising a train to proceed in an east bound direction

over the track section TE, when the signal lever SL is in a right-hand extreme position.

With the track section TE unoccupied, the track relay T is energized by the battery 13 in the usual well known manner, which causes the front contact 15 of said track relay T to complete the circuit for the section locking relay SLR. This energizing circuit is traced as follows:—from the positive terminal of a suitable source of electrical potential indicated as B+, through front contact 15 of track relay T, wire 16, winding of relay SLR, to the negative terminal of the suitable source indicated as B-.

The section locking relay SLR governs the normal and reverse energizing circuits of the remote controlled relay Z¹. The normal energizing circuit of this relay Z¹ is traced as follows:—from the positive terminal of battery BT¹, through wire 18, lever SML in a right-hand extreme position, wire 19, winding of the indicating relay IR, wire 20, front contact 21 of relay SLR, wire 22, winding of relay Z¹, wire 23, front contact 24 of relay SLR, through the common wire C¹ to the midpoint of the battery BT¹. The control relay Z¹ has its polar contacts thus energized to right-hand extreme positions.

With the polar contact 25 of relay Z¹ in a right-hand extreme position, the energizing circuit of the switch repeating relay SR is completed which also includes the holding circuit of the circuit controller CR. This normal energizing circuit for relay SR is traced as follows:—from the positive terminal of a suitable source of electrical potential indicated as B+, through back contact 26 of indicating relay RI, wire 27, polar contact 25 of relay Z¹ in a normal position, wire 28, winding NC of circuit controller CR, wire 29, contact 30 in a left-hand normal position, wire 31, contacts 7—32, wire 33, shunt contact 10, wire 34, winding of relay SR, wires 35 and 36, contacts 8—37, wires 38 and 39, to the negative terminal of the suitable source indicated as B-.

The energizing circuit for the relay NI is completed, as the neutral front contact 40 of relay SR is in an energized position and the polar contact 41 of relay SR is in a left-hand normal extreme position, which energizing circuit is traced as follows:—from the positive terminal of a suitable source of electrical potential indicated as B+, through front contact 40 of relay SR, wire 45, polar contact 41 of relay SR in a left-hand position, wire 46, winding of relay NI, wire 47, back contact 48 of relay RI, to the negative terminal of the suitable source indicated as B-.

The signals S^a and S^b are interlocked through contacts on the relays NI and RI in a manner that the signal S^a may be cleared when the track switch TS is in a normal locked position, and the signal S^b may be

cleared when the track switch TS is in a reverse locked position. Thus, should the operator at this time move the control lever SL to a right hand position, the remote control relay Z² would be energized and complete the 70 energizing circuit for clearing the signal S^a.

Let us assume that the operator moves the signal lever SL to a right-hand extreme position, which energizes the relay Z² from the positive terminal of battery BT², through 75 wire 49, lever SL in a right-hand extreme position, wire 50, winding of relay Z², common wire C², to the midpoint of battery BT². The circuit for clearing signal S^a is now completed with the front contact 51 of relay Z² in 80 an energized position. This circuit is traced as follows:—from the positive terminal of a suitable source of electrical potential indicated as B+, through front contact 51 of relay Z², wire 52, polar contact 53 of relay Z² 85 in a right-hand position, wire 54, back contact 55 of relay RI, wire 56, front contact 57 of relay NI, wire 58, through the control devices of signal S^a, to the negative terminal of the suitable source indicated as B-.

If a train accepts signal S^a and passes onto the track section TE, the fact is indicated in the tower TR by the illumination of the indicator lamp I. This is accomplished by the deenergization of the track relay T which in 90 turn opens the circuit of the section locking relay SLR. The dropping of the front contacts 21 and 24 of the relay SLR opens the normal energizing circuit of the relay Z¹ and shunts the winding of this relay through wire 22, back contact 21 of relay SLR, wire 59, back contact 24 of relay SLR, wire 23, to the opposite side of the winding of relay Z¹. The opening of the energizing circuit for the relay Z¹ also opens the energizing circuit of the indicating relay IR which causes its contact 65 to assume a deenergized position illuminating the indicator light I from the positive terminal of a suitable source of positive potential indicated as B+, through back contact 65 of relay IR, wire 66, indicator lamp I, to the negative terminal of the suitable source indicated as B-. With the indicating relay IR deenergized, the lock L is deenergized due to the opening of front contact 65 as is obvious from the drawing, which condition causes its locking member 62 to assume a position preventing movement of the switch machine lever SML. 100

Let us now assume, that there is no train on the track section TE, and that the various route locking, other similar locking relays and track relay T are in energized positions, so that the section locking relay SLR is energized. The indicator relay IR is now energized so that the locking member 62 of the lock L is actuated to an inactive position. Also, let us assume, that the operator moves the switch machine control lever SML to the left-hand position which energizes the relay 110 115 120 125 130

- Z¹ with negative potential through a circuit traced as follows:—from the negative terminal of battery BT¹, through wire 67, lever SML in a left-hand extreme position, wire 19, winding of relay IR, wire 20, front contact 21 of relay SLR, wire 22, winding of relay Z¹, wire 23, front contact 24 of relay SLR, common wire C¹, to the midpoint of battery BT¹.
- With the reverse energizing circuit completed for the relay Z¹, its polar contacts 25 and 70 are caused to assume a left-hand extreme position which opens the holding circuit of the controller CR and deenergizes the relay SR at the polar contact 25. The polar contact 70 of relay Z¹, thus completes the energizing circuit of the coil RC for controlling the contacts of the circuit controller CR to right-hand extreme positions, as soon as both the relays NI and RI assume deenergized positions. This energizing circuit for operating coil RC is traced as follows:—from the positive terminal of a suitable source of electrical potential indicated as B+, through back contact 71 of relay NI, wire 72, polar contact 70 of relay Z¹ in a left-hand extreme position, wire 73, coil RC, wire 74, contact 75 of circuit controller CR, wires 76 and 77, front contact 78 of relay T, wire 79, front contact 80 of relay SLR, wire 81, back contact 82 of relay NI, wire 83, back contact 84 of relay RI, to the opposite terminal of the suitable source indicated as B-. It will be noted that the contact 75 is a break-beyond-center contact, which insures that the mechanical toggle arrangement will cause the reverse contacts to be made.
- The contacts of the circuit controller CR are now operated to right-hand reverse extreme positions, in which positions a circuit is completed for operating the switch machine SM to a reverse position and thus control the track switch TS to a corresponding position. This reverse operating circuit for the switch machine SM is traced as follows:—from the positive terminal of a suitable source indicated as B+, through contact 85 of circuit controller CR in a right-hand reverse position, wire 86, armature A, wires 87 and 88, contacts 5—89, wire 90 contact 91 of circuit controller CR in a right-hand reverse position, wire 92, field winding F, wire 93, winding of brake BR, to the opposite terminal of the suitable source indicated as B-.
- The switch machine SM now unlocks the track switch TS and operates it to a reverse extreme position in the usual well known manner, at the completion of which the movable contact 5 is operated to a reverse position opening the energizing circuit of the switch machine at contacts 5—89.
- As soon as the switch machine SM unlocks the track switch TS, the normal energizing circuit of the switch repeating relay SR is further opened due to the operation of the

point detector contacts PD. The movable contact block 6 is operated to an intermediate position which causes the normal energizing circuit of the relay SR to be further opened at the contacts 7—32 and 8—37. Also, the shunt contact 9 assumes a contacting position thus shunting the relay SR from its left-hand terminal through wire 35, shunt contact 9 in a contacting position, wire 94, shunt contact 10 in a contacting position, wire 34, to the left-hand terminal of relay SR, which causes the neutral contact 40 to assume a deenergized position during the operation of the track switch TS or at any such time that it is unlocked.

It will be noted, that should the operator fail to return the signal control lever SL to a central position, the signal S^a would be put to stop immediately as soon as the control relay Z¹ reached a new governing position, due to the deenergization of the switch repeating relay SR and the normal indicating relay NI. In other words, the clearing of a signal depends upon the energization of either relay NI or RI and the deenergization of one of them, while the operation of the switch machine depends upon the deenergization of both of said relays.

When the track switch TS has been operated to an extreme reverse locked position, the movable contact block 6 is operated to an extreme reverse position and the shunt contact 10 is actuated to a non-contacting position, which completed the reverse energizing circuit for the switch repeating relay SR and included therewith the reverse holding circuit of the circuit controller CR.

The reverse energizing circuit for the switch repeater relay SR is traced as follows:—from the positive terminal of a suitable source of electrical potential indicated as B+, through back contact 71 of relay NI, wire 72, contact 70 of relay Z¹ in a left-hand position, wire 73, reverse operating coil RC, wire 74, contact 75 in a right-hand reverse position, wire 98, contacts 8—99, wire 100, shunt contact 9 in a contacting position, wire 35, winding of relay SR, wires 34 and 101, contacts 7—102, wire 38 to the negative terminal of the suitable source indicated as B-. As the current in the winding of relay SR is flowing in a reverse direction, the polar contact 41 is actuated to a right-hand reverse position, after which the neutral contact 40 is actuated to an energized position. The reverse indicating relay RI is now energized through a circuit traced as follows:—from the positive terminal of a suitable source of electrical potential indicated as B+, through front contact 40 of relay SR, wire 45, polar contact 41 of relay SR in a right-hand position, wire 103 winding of relay RI, wire 104 back contact 105 of relay NI, to the negative terminal of the suitable source indicated as B-.

With the reverse indicating relay RI energized, the signal S^b may be caused to give a proceed indication for the passage of traffic in an east-bound direction over the track switch TS onto the passing siding PS. This is accomplished by the movement of the control lever SL to a left-hand position which places negative potential upon the control relay Z² from the negative terminal 10 of battery BT² through wire 106, lever SL in a left-hand position, wire 50, winding of relay Z², common wire C² to the mid-point of battery BT². The polar contact 53 of control relay Z² is now actuated to a left-hand reverse position and the neutral contact 51 is actuated to an energized position, which completes the circuit for signal S^b. This energizing circuit for the signal S^b is traced as follows:—from the positive terminal of a suitable source of electrical potential indicated as B+, through front contact 51 of relay Z², wire 52, polar contact 53 in a left-hand position, wire 107, front contact 108 of relay RI, wire 109, back contact 110 of relay NI, wire 111, through the control devices of signal S^b, to the negative terminal of the suitable source of potential indicated as B-.

Assuming that a train passes onto the detector track section TE, thence over the track switch TS onto the passing siding PS, the track relay T is deenergized in the usual manner which results in the deenergization of the indicator relay IR, and the lever lock L in the same manner as heretofore explained. Thus, indication is given in the tower of the passage of a train over the detector track section TE by the illumination of the indicating lamp I. Also, the switch machine control lever SML is prevented from being operated to a new position with the locking member 62 of lock L in an active position.

Assume the detector track sections to be unoccupied, then the control lever SML may be returned to its normal position, thus controlling the track switch TS to its normal position in an operation which is merely an inverse function of the operation of the system from the normal condition to reverse condition as just described in detail.

From the above description, it is obvious that the governing signals S^a and S^b cannot give clear or proceed indications during the operation of the switch machine SM, or conversely, the switch machine cannot be operated unless said governing signals display their most restrictive indications. In other words, as soon as the switch machine control lever is operated to a new position, the polar contacts of the control relay Z¹ are operated to new positions which open the circuit of the normal and reverse indication repeating relays NI and RI which must then assume deenergized positions before the switch ma-

chine circuit controller CR can be operated. When the indication repeating relays NI and RI assume deenergized positions to permit the operation of the circuit controller CR, the clearing circuits for the signals S^a 70 and S^b are necessarily open at a front contact.

The above description points out the various conditions governing the signals S^a and S^b which are involved in the manual establishment of the several routes. In other words, the signal circuits are interlocked with the associated switch machine control to prevent the false or improper clearing of a signal and to provide that it 80 shall give its most restrictive indication before the established route may be changed.

The signals are also under the control of an operator, which control allows the signals to be caused by the operator to give most restrictive indications at any time, and allows the circuits to be conditioned by the operator for the signals to give clear indications when the remaining conditions, not under the control of the operator, are such as to permit the clearing of the signals. These remaining conditions include those established by the interlocking as pointed out above and also preferably include conditions established in accordance with the traffic passing 95 through the established route. Such traffic conditions govern the signals by automatic control means operated by the track circuits of the various routes, which automatic means is associated with the signals 100 in a manner well known in the art, and is omitted for the sake of simplicity in the present disclosure.

By the provision of the lever lock L, the operations of the switch machine control lever SML and the control relay Z¹ are coordinated although the intervening control circuits are open at certain times for transmitting the indication of detector track section occupancy. Also, premature switch machine lever movement is prevented before the associated track switch is in condition to receive such control.

It may be further noted, that the switch repeating relay SR not only indicates the position and locked condition of the track switch TS, but also indicates the correspondence of the circuit controller CR and the control relay Z¹ with said switch TS. This interlocking of control operations and indication conditions prevents the clearing of any governing signal to permit the passage of a train, when any one of said elements are out of correspondence, which lack of correspondence might otherwise result in the operation of the track switch to an unlocked condition without proper authorization during the passage of a train.

Having described rather specifically an interlocking system embodying the present in- 130

vention, it is to be understood that the various circuits and devices included in this embodiment are used to facilitate in the disclosure of the invention, rather than to determine the specific nature and scope of the invention; also, it is to be understood that various modifications, adaptations and alterations may be made to the interlocking system embodying the present invention to meet the varying requirements of practice without departing from the spirit or scope of the present invention, as set forth in the appended claims.

Having described my invention, I now claim:

15. 1. In an interlocking system for railroads, a track switch having a detector track section, a switch machine for operating said track switch, a control lever, a control relay for governing said switch machine said relay being controlled by said control lever, means indicating in the tower the occupancy of said detector track section, and locking means preventing movement of said control lever to a new governing position during the indication of occupancy of said detector track section.
20. 2. In an interlocking system for railroads, a track switch having a detector track section, a switch machine for operating said track switch, a control lever, a control relay for governing said switch machine, said relay being controlled by said control lever over a polarized line circuit, an indicating relay included in series in said polarized line circuit, means for breaking said polarized line circuit during occupancy of said detector track section, whereby both said control and said indicating relays are deenergized, and locking means effective to prevent movement of said control lever to a new governing position when said indicating relay is deenergized.
25. 3. In an interlocking system for railroads, a track switch, a switch machine having normal and reverse operating circuits, a two-position circuit controller for closing said operating circuits, a two-position control relay governed from the tower, means causing said circuit controller to be operated to a position in correspondence with said control relay, an indication relay giving indication of the correspondence of said control relay and said circuit controller with said track switch, holding circuits for said circuit controller including said indication relay completed when said track switch is in correspondence with said control relay and said circuit controller, and signals governed by said indication relay.
30. 4. In an interlocking system for railroads, a track switch, a switch machine, a circuit controller for controlling said switch machine, a control relay operated from a distant point for controlling said circuit controller, a plurality of relays indicating the position and locked condition of said track switch and also the correspondence of said control relay and said circuit controller with said track switch, a plurality of signals governing traffic over said track switch and selected by said indication relays, means preventing operation of said circuit controller until said indication relays give indication of the non-correspondence of said control relay with said circuit controller, and means, including said indication relays, for insuring the non-selection of said signals except when said control relay and said circuit controller are in correspondence with said track switch.
35. 5. In an interlocking system for railroads, a track switch, a switch machine having normal and reverse operating circuits, signals governing traffic over said track switch, a two-position circuit controller of the mechanical stick type for controlling said switch machine a two-position relay operated from a remote point, said relay operably governing said circuit controller, an indication relay giving one indication when said track switch is in a normal locked position with said control relay and said circuit controller in correspondence therewith, giving another indication when said track switch is in a reverse locked position with said control relay and said circuit controller in correspondence therewith, and giving a third indication when said track switch is unlocked or when either said control relay or said circuit controller is out of correspondence with said track switch, two indication operating relays, one of which is energized when said indication relay gives said one indication, the other of which is energized when said indication relay gives said other indication, and both of which are deenergizing when said indication relay gives said third indication, means preventing the operation of said circuit controller except when both said indication repeating relays are deenergized, and means preventing the clearing of said signals when both of said indication repeating relays are energized.
40. 6. In an interlocking system for railroads, a track switch, a detector track section associated with said track switch, a switch machine for operating said track switch, a control lever, a control relay governed by said control lever over a polarized line circuit for causing said switch machine to operate, signals governing traffic over said detector track section, manually controlled means for clearing said signals, means causing said manually controlled means to be ineffective to clear said signals when said switch machine is in operation, and means preventing the operation of said switch machine during occupancy of said detector track section.
45. 7. In a railroad traffic controlling system, a track switch, a switch machine for operating said track switch, a two-position circuit controller for governing said switch machine, a remotely controlled relay, operating cir-

- cuits for said two-position circuit controller governed by said remotely controlled relay, holding circuits for said two-position circuit controller governed by said remotely controlled relay, a detector track section, means opening the operating circuits of said two-position circuit controller when said detector track section is occupied, and means preventing operation of said remotely controlled relay when said detector track section is occupied.
8. In a railroad traffic controlling system, a track switch, a switch machine for operating said track switch, a two-position circuit controller for governing said switch machine, a remotely controlled relay, operating circuits for said two-position circuit controller governed by said remotely controlled relay, holding circuits for said two-position circuit controller governed by said remotely controlled relay, a detector track section, means opening the operating circuits of said two-position circuit controller when said detector track section is occupied, and means preventing the opening of said holding circuits for said two-position circuit controller when said detector track section is occupied.
9. In a railroad traffic controlling system; a track switch; power actuated means for operating said track switch; an electro-responsive device for governing said power actuated means, said device being remotely controlled; indication means for indicating the position and locked condition of said track switch, said indication means being responsive to the correspondence between said electro-responsive device and said track switch; and signals governed by said indication means.
10. In a railroad traffic controlling system; a track switch operable to normal or reverse extreme positions; a power actuated means for operating and locking said track switch in either of said extreme positions; a manually controlled electro-responsive device for governing said power actuated means; point detector contacts operated by said track switch to opposite extreme positions in accordance with the normal or reverse extreme position of said track switch and actuated to intermediate positions when said track switch is unlocked; an indicating relay; operating circuits for said indicating relay governed by said point detector contacts and said manually controlled electro-responsive device, whereby said indicating relay is caused to indicate the condition of correspondence between said manually controlled electro-responsive device and said track switch and also to indicate the normal or reverse position of said track switch together with its locked or unlocked condition; and signals selected by said indicating relay.
11. In a railroad traffic controlling system, a track switch, a switch machine for operating said track switch, power actuated means for operating said track switch, an electro-responsive device for actively governing said power actuated means when said electro-responsive device is operated out of correspondence with said track switch, indication means indicating the position and locked condition of said track switch, means causing said indication means to give an indication corresponding to the unlocked condition of said track switch when said electro-responsive device is actuated out of correspondence therewith, and traffic controlling means governed by said indication means.
12. In a railroad traffic controlling system, a railroad track switch, power actuated means for operating said track switch, an electro-responsive device for actively governing said power actuated means when said electro-responsive device is operated out of correspondence with said track switch, indication means indicating the position and locked condition of said track switch, means causing said indication means to give an indication corresponding to the unlocked condition of said track switch when said electro-responsive device is actuated out of correspondence therewith, and traffic controlling means governed by said indication means.
13. In a railroad traffic controlling system, a railroad track switch, power actuated means for operating said track switch, an electro-responsive device for actively governing said power actuated means when said electro-responsive device is operated out of correspondence with said track switch, indication means indicating the position and locked condition of said track switch, means causing said indication means to give an indication corresponding to the unlocked condition of said track switch when said electro-responsive device is actuated out of correspondence therewith, and means preventing said electro-responsive means from actively governing said power actuated means until said indication means gives an indication corresponding to the unlocked condition of said track switch.
14. In a railroad traffic controlling system, a railroad track switch, power actuated means for operating said track switch, an electro-responsive device for actively governing said power actuated means when said electro-responsive device is operated out of correspondence with said track switch, indication means indicating the position and locked condition of said track switch, means causing said indication means to give an indication corresponding to the unlocked condition of said track switch when said electro-responsive device is actuated out of correspondence therewith, means preventing said electro-responsive

sive means from actively governing said power actuated means until said indication means gives an indication corresponding to the unlocked condition of said track switch, and
5 other traffic controlling means governed by said indication means.

15. In an interlocking system for railroads, a track switch, a switch machine for operating said track switch, means for controlling said switch machine, signals governing traffic over said track switch, means for manually clearing said signals, means causing said signals to give most restrictive indications upon operation of said means for controlling said switch machine irrespective of said means for manually clearing said signals, means requiring said signals to give most restrictive indications before said switch machine can be controlled by said means for controlling said switch machine, and means preventing operation of said means for controlling said switch machine during the passage of traffic over said track switch.

In testimony whereof I affix my signature.
FRANK L. DODGSON.

sive means from actively governing said power actuated means until said indication means gives an indication corresponding to the unlocked condition of said track switch, and 5 other traffic controlling means governed by said indication means.

15. In an interlocking system for railroads, a track switch, a switch machine for operating said track switch, means for controlling said switch machine, signals governing traffic over said track switch, means for manually clearing, said signals, means causing said signals to give most restrictive indications upon operation of said means for controlling said switch machine irrespective of said means for manually clearing said signals, means requiring said signals to give most restrictive indications before said switch machine can be controlled by said means for 20 controlling said switch machine, and means preventing operation of said means for controlling said switch machine during the passage of traffic over said track switch.

In testimony whereof I affix my signature.
25 FRANK L. DODGSON.

DISCLAIMER

1,824,127.—*Frank L. Dodgson, Rochester, N. Y. INTERLOCKING SYSTEM FOR RAILROADS. Patent dated September 22, 1931. Disclaimer filed July 28, 1934, by the assignee, General Railway Signal Company.*

Hereby enters this disclaimer to claims 6, 7, 8, and 15 of said Letters Patent, which are in the following words, to wit:

“6. In an interlocking system for railroads, a track switch, a detector track section associated with said track switch, a switch machine for operating said track switch, a control lever, a control relay governed by said control lever over a polarized line circuit for causing said switch machine to operate, signals governing traffic over said detector track section, manually controlled means for clearing said signals, means causing said manually controlled means to be ineffective to clear said signals when said switch machine is in operation, and means preventing the operation of said switch machine during occupancy of said detector track section.

“7. In a railroad traffic controlling system, a track switch, a switch machine for operating said track switch, a two-position circuit controller for governing said switch machine, a remotely controlled relay, operating circuits for said two-position circuit controller governed by said remotely controlled relay, holding circuits for said two-position circuit controller governed by said remotely controlled relay, a detector track section, means opening the operating circuits of said two-position circuit controller when said detector track section is occupied, and means preventing operation of said remotely controlled relay when said detector track section is occupied.

“8. In a railroad traffic controlling system, a track switch, a switch machine for operating said track switch, a two-position circuit controller for governing said switch machine, a remotely controlled relay, operating circuits for said two-position circuit controller governed by said remotely controlled relay, holding circuits for said two-position circuit controller governed by said remotely controlled relay, a detector track section, means opening the operating circuits of said two-position circuit controller when said detector track section is occupied, and means preventing the opening of said holding circuits for said two-position circuit controller when said detector track section is occupied.”

“15. In an interlocking system for railroads, a track switch, a switch machine for operating said track switch, means for controlling said switch machine, signals governing traffic over said track switch, means for manually clearing said signals, means causing said signals to give most restrictive indications upon operation of said means for controlling said switch machine irrespective of said means for manually clearing said signals, means requiring said signals to give most restrictive indications before said switch machine can be controlled by said means for controlling said switch machine, and means preventing operation of said means for controlling said switch machine during the passage of traffic over said track switch.”
